E. DIETZ

WAREHOUSE TRUCK

Filed March 13, 1923

Inventor
Emil Dietz

By

Emil Dietz

Attorney

UNITED STATES PATENT OFFICE.

EMIL DIETZ, OF INDIANAPOLIS, INDIANA, ASSIGNOR TO CARL V. DIETZ, OF INDIANAPOLIS, INDIANA.

WAREHOUSE TRUCK.

Application filed March 13, 1923. Serial No. 624,752.

To all whom it may concern:

Be it known that I, EMIL DIETZ, a citizen of the United States, residing at Indianapolis, in the county of Marion and State of Indiana, have invented certain new and useful Improvements in Warehouse Trucks, of which the following is a specification.

My said invention relates to a warehouse truck and the specific improvement is directed to a corner iron for such trucks. It is an object of my invention to provide a truck which shall be of very simple design but strong and well adapted for its purpose.

15 A further object of the invention is to provide a bracket which shall be adapted without change or modification of structure to support either a loose standard or a fixed standard for the truck.

20 Referring to the accompanying drawings which are made a part hereof and on which similar reference characters indicate similar parts,

Figure 1 is a plan of a preferred form of 25 my device,

Figure 2 a section on line 2—2 of Figure 1,

Figure 3 a plan of a modified form,

Figure 4 a section on line 4—4 of Figures 30 3 and 5, and

Figure 5 an elevation looking in the direction of the arrow on Figure 4.

In the drawings reference character 10 indicates the swivel board of a truck of 35 well-known type, said truck being provided with side rails 11 and end rails 12, the side rail 11 here being shown as having a mortise engaged by a tenon on the end rail. An inner corner iron 13 preferably extending

40 through the swivel board to the top of the rails is secured by bolts 14 and 15 to the side and end rails respectively, these bolts extending also through adjacent parts of the outer bracket for holding the same. It

45 will be understood that there may be two or more in each set of bolts. Obviously also the brackets may be attached at the side of the truck as in lumber trucks, the swivel board may be omitted and other 50 changes may be made in a manner obvious or customary in the art.

An outer corner iron 16 has extensions in each direction from the corner to engage the side and end rails, said extensions being held in place by the bolts 14 and 15. The

end rail is cut away on a line with the tenon to form a recess to receive one side of a socket in the iron adapted to receive a loose standard 17, this standard in the modification of Figure 1 resting on a projecting part of the swivel board 10. It will be seen that the side of the socket adjacent the end rail fits closely between the side rail 11 and a shoulder on the end rail to assist in making a strong and rigid interlocking corner for the truck. Registering holes may be provided in the parts to receive a bolt 18 in case it is found desirable to use fixed standards, and a single bolt is enough to hold the standard securely in place.

In the modification of Figures 3, 4 and 5 the parts are generally similar to what has heretofore been described, the size of the end and side rails being such, however, that 55 their edges correspond to the edges of the swivel board. Under such conditions the swivel board cannot be depended on to support standard 17 at its lower end and therefore I have shown in these figures a ledge 19 on the outer corner bracket extending across the lower end of the socket and providing a support for the standard.

While I have shown and described preferred forms of my invention various changes of form and structure will be obvious to those skilled in the art and therefore I do not limit myself to what is shown in the drawings and described in the specification but only as indicated in the appended 90 claims.

Having thus fully described my said invention, what I claim as new and desire to secure by Letters Patent, is:

1. In a truck, a swivel board, side and end rails secured thereto, inner and outer corner irons for securing the rails together at the corners of the truck, bolts passing respectively through one of said rails and both of said irons to hold the parts in place said outer iron having a socket for a standard and said swivel board extending beneath the socket to support the standard, substantially as set forth.

2. In a truck, a swivel board, side and end rails secured thereto, inner and outer corner irons for securing the rails together at the corners of the truck, bolts each passing through one of said rails and both of said irons to hold the parts in place the outer 110

- corner iron having a socket and said swivel board extending beneath the socket to support the standard, the opposite walls of said socket having openings alined with openings 5 in the adjacent rail and in the inner bracket to receive a bolt extending through a standard to fix the same in place, substantially as set forth.
3. In a truck, an interlocking corner structure 10 comprising a swivel board, end and side members mortised together, and secured to said swivel board, inner and outer corner irons having angularly related parts to engage the respective side and end rails, means 15 for holding said irons in place and a socket on the outer corner bracket offset inwardly to cause the standard to rest at its lower end on the swivel board, substantially as set forth.
- 20 4. An interlocking corner structure for trucks comprising a swivel board, end and side rails mortised together and secured to said board, a corner iron provided with a socket, one side of said socket engaging be- 25 tween the side rail and a shoulder on the end rail, means for supporting a loose standard in the socket, and openings in the standard and the corner iron arranged to register

with each other and with an opening in the standard whereby the latter can be fixed in 30 place, substantially as set forth.

5. In a truck, an interlocking corner structure comprising end and side members mortised together, and an outer corner iron secured to the side and end members said iron 35 having a socket for a stake offset inwardly to engage between one of said members and a shoulder on the other, substantially as set forth.

6. In a truck, an interlocking corner 40 structure comprising end and side members mortised together, an outer corner iron secured to the side and end members said iron having a socket for a stake offset inwardly 45 to engage between one of said members and a shoulder on the other, and a ledge beneath the socket to engage with and support said stake, substantially as set forth.

In witness whereof, I have hereunto set my hand and seal at Indianapolis, Indiana, 50 this 9th day of March, A. D. nineteen hundred and twenty-three.

EMIL DIETZ. [L.S.]
